(57) **CLAIM**

The ornamental design for a pet dish stand, as shown and described.

DESCRIPTION

FIG. 1 is a perspective view of a pet dish stand, showing my new design;

FIG. 2 is a bottom perspective view of FIG. 1;

FIG. 3 is a top plan view of FIG. 1;

FIG. 4 is a bottom plan view of FIG. 1;

FIG. 5 is a right side elevation view of FIG. 1, the left side elevation view being a mirror image thereof; and,

FIG. 6 is a front elevation view of FIG. 1.

The pet dish stand shows synthetic turf thereon.
